UNITED STATES PATENT OFFICE.

CHARLES E. CLARK, OF BELMONT, NEW YORK.

FEED MECHANISM FOR SAW-MILL CARRIAGES.

SPECIFICATION forming part of Letters Patent No. 351,165, dated October 19, 1886.

Application filed August 31, 1885. Serial No. 175,770. (No model.)

To all whom it may concern:

Be it known that I, CHARLES E. CLARK, a citizen of the United States, residing at Belmont, in the county of Allegany and State of New York, have invented certain new and useful Improvements in Saw-Mill-Carriage Feeds, of which the following is a specification, reference being had therein to the accompanying drawings, in which—

10 Figure 1 is a side view of my steam-feed; Fig. 2, a detail of the drum, racks, &c. Fig. 3 is a modification.

This invention relates to certain new and useful improvements in that class of saw-mill feeds 15 which are operated by an independent steam-cylinder and connections; and the invention consists in the peculiar combinations and the construction and arrangement of parts, hereinafter more particularly described and claimed.

20 Referring now to the details of the drawings by letter, A represents the carriage-way; B, the carriage running thereon, provided with the usual rollers or wheels, b, and having connected to it a wire rope, C, which passes over sheaves D at each end of the carriage-way, and has its ends coiled around and connected to the drum E, although it may, if preferred, have its ends connected to the carriage and its center coiled around the drum a sufficient number 25 of times to hold fast thereto by friction.

30 F is a steam-cylinder provided with a piston (shown in dotted lines) and a piston-rod, G, carrying a yoke, H, in which runs a short shaft, I, on which is securely fastened the drum E, and two pinions, J, which mesh into racks K, firmly fastened to an extension of the cylinder-bed L.

35 At M is a lever, pivoted at m to the carriage-way or to some other convenient fixed part of 40 the frame, and connected with a bell-crank lever, N, by a rod, O, pivoted to both levers. The lever N is connected with the stem P of the valve Q, which has pipes R leading to the opposite end of the cylinder. The lower end 45 of the lever has a strap, S, which carries a weight, T, which strap passes between two pulleys, U, so that any motion of the lever from the position shown will raise the weight, and the latter will consequently tend to always 50 keep the lever in its present or normal position in which the steam is shut off, and the piston consequently remains stationary. This ar-

angement of the lever, weight, valve, &c., is well known, and it is therefore unnecessary to further describe it.

55 It will be observed that the sheaves D are so arranged relative to the drum as to guide the rope C over the drum in such a manner as to cause said rope C to press on the drum E, and thus cause the pinions to always remain 60 in their proper position upon the rack. Without this arrangement of the sheaves, rope, &c., there would have to be guides to keep the pinions from rising out of the rack and the expense and friction due to the making and use 65 of such guides is thus dispensed with.

The operation of the apparatus can be readily seen, and it seems unnecessary to describe it at length. It is sufficient to state that with the lever in its present position steam is shut 70 off from the cylinder and the carriage is at rest; but if the lever M is moved steam is admitted to one end of the cylinder or the other, according to the direction the lever is moved, which steam operates the piston and moves the yoke 75 H, which drives the pinions over the racks and causes the drum to turn, thus winding up one end of the rope and unwinding the other, thereby giving motion to the carriage.

75 Instead of the racks and pinions a drum, e, 8c on each end of the main drum-shaft, may be used, as shown in Fig. 3, and ropes e wound around these drums with their ends attached to studs l on the bed L. From this it will be seen that modifications may be made in the details of construction without departing from the spirit of my invention.

85 I am aware of the Patent No. 176,409, in which a vibrating toothed segment is used to operate a pinion and drum and revolve the 90 same in opposite directions, and therefore make no claim, broadly, to the use of a pinion and drum and mechanism for operating the same in opposite directions. My arrangement, however, differs essentially from this in that the 95 cylinder and drum are arranged nearly or substantially in the same horizontal plane, and the straight rack which I employ in lieu of the segment takes up little or no additional space and is much stronger. The apparatus is thus 100 rendered much more compact, whereby space is economized, and as the action between the piston and drum is substantially in a direct line, and as the rack is stronger than the

toothed segment, the mechanism may be much lighter and there is less danger of breaking.

What I claim as new is—

1. The combination of a saw-mill carriage, 5 a frame supporting the same, a guide-sheave near each end of said frame, a drum reciprocating and revolving in opposite directions alternately, and a rope connected with the carriage and passing around the sheaves to the 10 drum, with a cylinder, a piston and its rod working therein, and a straight rack, all arranged in substantially the same horizontal plane as the drum, and a pinion fast on the drum-shaft, meshing with the rack and revolving 15 in opposite directions, and of smaller diameter than said drum, and arranged to cause the drum to wind the rope upon itself in opposite directions alternately, substantially as described.
- 20 2. The combination of a saw-mill carriage, of a cylinder and piston, a pinion and a drum rigidly connected with each other and having the shaft on which they turn reciprocated in opposite directions by the motion of the piston, 25 a rack into which said pinion meshes, and a rope wound in opposite directions alternately around said drum and connected to the carriage, substantially as described.
3. The combination, with a saw-mill car-

riage, of a cylinder, a piston and rod working therein, a yoke connected to the piston-rod, a drum rigidly attached to a shaft working in said yoke, two pinions fixedly mounted on the shaft of said drum, two racks arranged on opposite sides of the drum and meshing 35 with said pinions, and a rope wound in opposite directions alternately around said drum and connected to the carriage, all substantially as described.

4. In a rope feed saw-mill, the combination 40 of a drum, a rack, and a pinion, with the guide for the rope arranged to hold said rope below the top of the drum to press the pinions down upon the rack, substantially as described.

5. In a rope-feed for saw-mills, the combination 45 of a traveling drum, a rack, a pinion secured to the drum traveling over said rack, and a rope wound around said drum and connected to the carriage, with guide-sheaves for the rope which press the drum and pinion downward, 50 substantially as described.

In testimony whereof I affix my signature in presence of two witnesses.

CHARLES E. CLARK.
